UNITED STATES PATENT OFFICE

CHARLES W. MEVES, OF SHEBOYGAN, WISCONSIN, ASSIGNOR TO SHEBOYGAN COUCH COMPANY, OF SHEBOYGAN, WISCONSIN, A CORPORATION OF WISCONSIN

BED DAVENPORT

Application filed April 30, 1923. Serial No. 635,579.

The invention relates to davenport and more particularly to that type of davenport convertible into a bed.

The object of the invention is to simplify and improve upon the type of davenport shown in United States Letters Patent No. 1,349,622, dated September 17, 1920, to Charles W. Meves and Frederick G. Herrmann, by simplifying the linkage construction for the bed sections and by making the construction so compact that the height of the seat is no greater than that of the usual fixed seat davenport.

The invention further consists in the several features hereinafter set forth and more particularly defined by claims at the conclusion hereof.

In the drawings: Fig. 1 is an end view of a bed davenport embodying the invention, shown in closed position, one end thereof being removed; Fig. 2 is a view similar to Fig. 1, showing the davenport converted into a bed; Fig. 3 is a detail sectional view taken on the line 3—3 of Fig. 1; Fig. 4 is a detail plan view of a part of the device; Figs. 5 and 6 are views similar to Fig. 1, showing the parts in intermediate positions.

In the drawings the numeral 5 designates an end frame, the other similar end frame not being shown in detail, but both connected to a fixed back 6.

A pair of plates 7 are preferably detachably connected to the end frames by means of screws 8 or other suitable fastening means. All the moving parts of the davenport are carried by these plates which may be readily attached to the davenport.

A front rail 9 is fixed to the end frames by the plates 7 each of which has a flange portion 10 secured to the front rail by screws 11. A hook-shaped swinging arm 12 is pivotally mounted at its lower end on a pin 13 secured to each plate adjacent the lower parts of the front rail.

The upper forwardly projecting end of each arm 12 is pivotally connected by a pin 14 to the frame of the seat member or cushion 15 near the front end thereof. On the pivotal connections thus formed the seat may be inverted from its upright position, shown in

Fig. 1, to its inverted position shown in Fig. 2. The shape of the arms provides the necessary clearance for the turning of the seat. When in the position shown in Fig. 1 each arm engages a stop pin 16 limiting its backward movement and the sides of the frame of the seat member adjacent the rear portion thereof rest upon ledges 17 provided by brackets 18 secured to the end frames.

The seat member 15 has links 19 pivotally secured to its frame near its rear end. A bed section 20 is pivotally connected to said links 19. Another bed section 21 is connected to the first bed section 20 through an intermediate hinge section including links 22. These links 22 are pivotally mounted intermediate their ends upon pins 23 carried by brackets 24 secured to the frame of the seat member near the front end thereof. The links 22 are also secured to a transversely extending brace bar 25.

The bed sections are provided with the usual spring fabric supporting structure. The rear portion of the bed section 21 carries brackets 26 at its sides having curved slots 27 formed therein. Legs or links 28 are, each pivotally connected at their forward ends to the adjacent plate 7, by a pin 29, and each leg carries at its other end a pin 30 slidably movable in the slot 27. These legs 28 support the rear part of the bed when the seat is inverted.

To hold the hinge links 22 aligned with the adjacent frame members of the bed section 21 during a part of its movement, each link carries a laterally projecting arm 31 connected to one end of a tensioned coil spring 32, the other end of said spring being secured to the adjacent frame member of said bed section 21.

Angled brackets 33 secured to the end frames 5 form stops for the legs 28 when the parts are in collapsed or folded position. The upper edge 34 of the front rail 9 is rearwardly bevelled and faced with a metal wear plate 35.

The rear bed section 21 is provided with pins 36 which engage the legs 28 adjacent thereto when said bed section is raised and cause the pins 30 to move to and be held in

the forward ends of the slots 27, as shown in Fig. 2.

To change the device to its bed form the operator grasps the rear end of the seat and 5 draws it upwardly and forwardly to inverted position. On the first part of the upward movement of the seat member the swinging of the arms 12 toward the front rail brings the hinge links 22 against the plate 35 upon 10 which the links slide upwardly until the front edges of the arms 12 abut against the front rail. Following this the seat member swings about the then stationary arms and during the first part of this movement the 15 links 22, by the action of the springs 32, straighten out into alignment with the adjacent frame members of the bed section 21 and the bed section moves rearwardly so that the pins 30 are positioned in the forward part of 20 the slots 27, as shown in Fig. 5. On the movement from the position shown in Fig. 5 to that shown in Fig. 6, with the seat slightly beyond the vertical position, the bed section 21 has lifted and moved forwardly relative 25 to the legs 28 to bring the pins 30 to the rear ends of the slots 27, thereupon lifting the legs 28 and effecting the engagement of their lower edges with the pins 36, which then assume a lifting function and simultaneously move 30 the pins 30 forwardly in the slots 27. During the movement of the seat from the position shown in Fig. 6 to that shown in Fig. 2, the legs 28 are raised to bed-supporting position and by the action of the pins 36 the free ends 35 of the legs are swung to the forward ends of the slots 27. Simultaneously the bed sections 20 and 21 are swung into aligned position parallel to the floor. In this position the bed sections are supported from the seat and the end frames by the links 19, the brackets 24, and 40 the legs 28. The usual folding legs 36 on the seat are swung down to supporting position to prevent tipping of the bed.

To return the parts to closed position the 45 movements of the seat member are reversed and the bed sections are swung into the position shown in Fig. 1 with the rear portions of the seat resting on the ledges 17 and the arms 12 abutting the stop pins 16. During this 50 closing movement the legs 28 swing down against the stops 33 as the seat member swings about the arms 12, and further swinging movement of the seat member brings the upper portions of the hinge links 22 into sliding 55 contact with the front rail and the continued movement of said seat member swings them out of line with the bed section 20 and to the position shown in Fig. 1; the pins 30 moving in the slots 27 to accommodate these 60 movements.

It will be noted that the arms 12 swing forward as the seat section is raised into abutting engagement with stops, which in the present instance are the flanges 10 on the 65 plates, and at this time the pivotal connections

between the seat and the forwardly projecting portions of the arms have been moved far enough in front of the front rail to permit inversion of the seat without interference with the front rail. This feature is important and an improvement over the structure shown in the patent previously referred to because it obviates the use of slots between the front rail and the end frames and thereby greatly strengthens the construction and makes it simpler and easier to assemble. It is not necessary that the hinge section 22 ride on the front rail but by employing this feature the parts may be more compactly folded together and the swinging arms may be brought close to the front rail.

The desirability and functions of the engagement of the hinge section 22 with the front rail, and also of the lost motion between the rear end of the bed section 21 and the end frames, will be apparent from an inspection of Figs. 5 and 6. It will be seen that while the hook-shaped arms 12 remain in engagement with the front rail, the pivotal connection 23 between the seat and the hinge portion 22 traverses a circular path about a fixed center. During the closing movement of the seat it is necessary to break the joint between the hinge section 22 and the rear bed section 21, and this is accomplished by providing a reaction support for the forward end of the hinge section, about which the hinge section may swing downwardly upon the descent of the bracket 24, which latter then exerts a lateral pressure on the hinge section. The hinge joint is thus effectively broken without subjecting it to unnecessary stress in the plane of the bed frame members. The direct imposition of a lateral pressure on the joint in order to break the joint is particularly desirable when the joint members are urged into alignment by constantly acting means, such as springs. In the present instance, the top edge of the front rail forms a convenient reaction support and the sliding engagement of the hinge section thereon permits both the rotation and translation of the hinge section, particularly during the closing movement of the davenport, but also during the opening movement. By constraining the movement of the linkage in this manner, it is also possible to secure greater compactness of construction than would otherwise be feasible.

The lost motion connection between the rear end of the bed section and the end frames is provided to insure the smooth working of the linkage without any tendency toward binding, particularly when the bed sections and the legs 28 approach parallelism. As previously noted, the hinge connection 23, when in the region of the position shown in Fig. 5, traverses a circular path about a fixed center, and since the hinge section 22 and the bed section 21 then tend to assume their

aligned position, it will be evident that the hinged connections between them and between the bed section 21 and legs 28 would be subject to severe pressures in the plane of the bed section if the rear end of the bed section 21 were not free to move with respect to its connection with the end frames. The pin-and-slot connection, in addition to affording a linkage that operates smoothly, rapidly and positively, also permits greater compactness than would be otherwise possible. The pin-and-slot connection is effective to insure smooth operation during the folding and unfolding operations of the davenport but is rendered ineffective to permit relative movement in the bed-forming position of the davenport, as shown in Fig. 2, by the locking pin 36, which retains the bed supporting leg in a definite supporting position at one end of the slot 27.

With the construction above described such a compact arrangement is provided as to keep the height of the seat within the limits usually employed on unconvertible davenports.

I desire it to be understood that this invention is not to be limited to any specific form or arrangement of parts except in so far as such limitations are specified in the claims.

What I claim as my invention is:

1. In a bed davenport, the combination with end frames and a fixed front rail, of a pair of seat-supporting arms pivotally mounted behind said rail and each having a forwardly projecting upper end adapted to swing past the upper edge of said rail, a seat member pivotally mounted on the projecting upper ends of said arms and invertible thereabout when said arms have been swung forwardly, bed frame supporting legs pivotally mounted on said end frames, and an articulated bed frame operatively connected to said seat member and legs and movable to bed-forming position on the inversion of the seat member, said bed frame comprising front and rear bed sections and an intermediate hinge section movable into alignment, and said hinge section being pivotally connected intermediate its ends to said seat member and having at its forward end a sliding reaction support on the front rail during its travel to stored position, whereby the descent of the seat member breaks the joint between the intermediate hinge section and the rear bed section by a rotation and translation of said hinge member.

2. In a bed davenport, the combination with end frames and a fixed front rail, of a pair of seat-supporting arms pivotally mounted behind said rail for limited swinging movement and each having a forwardly projecting end adapted to swing past the upper edge of said rail, a seat member pivotally mounted on the projecting upper ends

of said arms and invertible thereabout when said arms have been swung forwardly, an articulated bed frame including a hinge section pivotally connected to said seat member and a rear bed section pivotally connected to said hinge section and movable into alignment therewith, the pivotal connection between said seat member and said hinge section describing during part of its operative movement an arc about its fixed center, bed frame supporting legs pivotally mounted on said end frames and each having a pivotal lost motion connection at their free ends with said rear bed section, whereby abnormal stresses on the pivotal connections of the bed frame linkage are avoided during the travel of the linkage and at a time when said bed frame supporting legs and said rear bed section approach parallelism, and means for preventing play at said lost motion connection when said bed frame is in bed-forming position.

3. In a bed davenport, the combination with end frames and a fixed front rail, of a pair of seat-supporting arms pivotally mounted behind said rail and each having a forwardly projecting upper end adapted to swing past the upper edge of said rail, a seat member pivotally mounted on the projecting upper ends of said arms and invertible thereabout when said arms have been swung forwardly, an articulated bed frame comprising front and rear bed sections and an intermediate hinge section all movable to aligned bed-forming position, links connecting the front end of said front bed section with said seat member, a pivotal connection between said hinge section and said seat member, the latter pivotal connection describing during part of its operative movement an arc about a fixed center, spring means acting to align said hinge section with said rear bed section, bed frame supporting legs pivotally mounted on said end frames and each having a pin-and-slot connection at their free ends with said rear bed section, whereby abnormal stresses on the pivotal connections of the bed frame linkage are avoided during the travel of the linkage and at a time when said bed supporting legs and said rear bed section and aligned hinge section approach parallelism, and whereby the spring influenced joints of the bed frame may be broken without restraint by said bed-supporting legs.

4. In a bed davenport, the combination with end frames and a fixed front rail, of a pair of forwardly swinging arms pivotally supported behind said rail and movable into abutting engagement therewith, a seat member pivotally mounted on the free ends of said arms, bed frame supporting legs pivotally connected to said end frames, front, intermediate and rear bed sections, links connecting the forward portion of said front bed section with said seat member, said intermediate

bed section forming a hinge connection between the other bed sections and pivotally connected with said seat member, pin and slot connections between the free ends of said legs and the rear portion of the rear bed section, springs acting to aline said intermediate section with the rear bed section, said intermediate bed section having sliding engagement with the upper edge of the front rail as the seat is moved to alternative positions, means for holding the seat in operative position, and means for limiting the movement of said legs.

5. In a bed davenport, the combination with end frames and a fixed front rail, of a pair of forwardly swinging arms pivotally supported behind the front rail and having their free ends movable over and in front of said rail, a seat member pivotally mounted on the free end of said arms, bed frame supporting legs pivotally mounted on said end frames, an articulated bed frame comprising front and rear bed sections and an intermediate hinge section, means connecting the front end of said front bed section with said seat member, a pivotal connection between said hinge section and said seat member, pin and slot connections between the free ends of said legs and the rear portion of the rear bed section, and means on the rear bed section engageable with said legs and cooperating with said pin and slot connections to swing the legs forwardly to a supporting position as said bed frame is moved to bed-forming position.

6. In a bed davenport, the combination with end frames and a front rail extending therebetween, of a pair of seat-supporting arms pivotally mounted behind the lower parts of said front rail and each having an upper end adapted to swing forwardly past said front rail, a seat member pivotally mounted on the upper ends of said arms and invertible thereabout when said arms have been swung forwardly, an articulated bed frame operatively connected to said seat member and to said end frames and movable to bed-forming position on the inversion of the seat member, said bed frame including a rear bed section, bed frame-supporting legs pivotally mounted on said end frames and each having a pivotal lost motion connection at its free end with said rear bed section for avoiding abnormal stresses on the pivotal connections of the bed frame linkage during the travel of the linkage and at a time when said bed frame-supporting legs and said rear bed section approach parallelism, and means for preventing play at said lost motion connection when said bed frame is in bed-forming position.

7. In a bed davenport, the combination, with end frames and a fixed front rail extending therebetween, of a pair of seat-supporting arms pivotally mounted behind the

front rail for limited angular displacement and each having a forwardly projecting upper end adapted to just clear the upper edge of said rail without substantial change in elevation, a seat member pivotally mounted at its bottom on the projecting upper ends of said arms and in its seat-forming position having its forward lower edge extending close to the upper edge of said fixed front rail, said seat member being invertible about its pivotal mountings when said arms are swung forwardly, and a bed member having an articulated connection with said seat member and with said end frames and movable to elevated bed-forming position on the inversion of said seat member.

8. In a bed davenport, the combination with a frame, of a seat member, supporting means on which said seat member is pivotally mounted for inversion, a bed member having an articulated connection with said seat member and movable to elevated bed-forming position on the inversion of said seat member, links pivotally connecting said frame and the rear portions of said bed member to support said portions in the elevated bed-forming position of said bed member, there being a pin-and-slot connection at one end of each link to avoid binding of the linkage when said links and bed member approach parallelism in their travel, the pin element of said pin-and-slot connection being carried on said link and the slot being formed in the member to which said link is pivotally connected at said connection, and a stop fixed with respect to each slot and engageable with the adjacent link to effect the travel of said pin element to one extreme position in said slot when said links approach the position in which they support the elevated bed member.

9. In a bed davenport, the combination of a frame, a movable seat member having an operative connection with said frame, a bed member operatively connected with said seat member and movable to elevated bed-forming position upon the conversion of the bed davenport to a bed, links pivotally connecting said frame and the rear portions of said bed member to support said portions in the elevated bed-forming position of said bed member, there being a pin-and-slot lost motion connection at one end of each link to prevent binding of the linkage, the pin element of said pin-and-slot connection being carried on said link and the slot being formed in the member to which said link is pivotally connected at said connection, and means for preventing play at said pin-and-slot lost motion connection when said bed frame is in bed-forming position.

In testimony whereof I affix my signature.
CHARLES W. MEVES.
